SIGMUND GESTETNER, OF LONDON, ENGLAND, ASSIGNOR TO D. GESTETNER LIMITED, OF LONDON, ENGLAND.

STENCIL SHEET AND STENCIL ADAPTED FOR USE IN DUPLICATING.

Application filed March 4, 1926, Serial No. 92,308, and in Great Britain March 20, 1925.

This invention relates to stencil sheets and stencils for use in duplicating manuscript, typewriting, drawings and the like.

5 Stencil sheets for the purpose indicated commonly comprise a sheet of highly porous material, such as Yoshino paper, provided with a coating of an ink-resisting composition.

10 In certain cases the stencil is produced by photographic means, while in others it is formed by stencilizing a stencil sheet with the aid of a style or in a typewriter or otherwise.

15 It is the general practice to secure such stencil sheets to a backing sheet, one purpose of which is to protect the stencil sheet during storage and transport while another purpose is to facilitate stencilizing by pressure, the backing sheet providing a support 20 for the stencil sheet during this operation.

In addition a portion of the backing sheet usually forms what is called the "heading" 25 of the stencil, that is to say the means whereby the stencil is secured in association with the inking means of the duplicating machine and when the stencil has been located on the machine the major portion of the backing sheet is removed, only the smaller section thereof which forms the heading being 30 left secured to the stencil sheet. To facilitate this detachment, the backing sheet is perforated or rouletted adjacent the upper end of the stencil.

35 For the majority of machines at present on the market, the matter is cut in the stencil on lines which will be parallel with the axis of the inking means of the machine.

40 In the specification of British Letters Patent No. 202,736 a duplicating machine of the kind in which the stencil is mounted on an endless flexible carrier travelling over a plurality of inking rollers is described and claimed which is adapted to produce simultaneously a stencil impression in a plurality 45 of colours. With a machine of this kind, in normal use, it is necessary that the stencil should be mounted upon the machine with the lines of matter cut in the stencil at right angles to the axis of the inking means.

50 With stencil sheets formed in the customary manner, in view of the length of the stencil sheet, it is not possible to insert the same in a typewriter having a carriage for

the usual quarto-sized paper so as to type thereon with the lines of matter running 55 parallel with the longer side of the sheet.

Moreover, with stencil sheets adapted for use with duplicators of the kind in which the stencil is secured to an endless flexible carrier running over a plurality of inking 60 rollers, it is not convenient to employ rollers of such a small diameter that a stencil sheet substantially less than 15" in length, measured from the base of the heading to the opposite end of the stencil, may be 65 employed.

The object of the present invention, broadly stated, is to provide an improved construction of combined stencil sheet or stencil, that is to say, an improved combination 70 of a stencil sheet or stencil with a backing sheet for use with such machines.

According to the present invention, one of the sides of the stencil sheet is secured throughout its length to the corresponding 75 side of the backing sheet and fastening means whereby the stencil is secured in association with the inking means of a duplicator are arranged or are adapted to be formed adjacent to the edge of the backing 80 sheet remote from the edge to which the edge of the stencil sheet is secured.

With this construction the whole or the greater portion of the backing sheet forms the so-called heading of the stencil and normally the backing sheet is not formed so that it may be readily detached from the sheet, although in one modification a detachable element forming a continuation of the backing sheet may be provided. 90

A combined stencil sheet in accordance with the invention, in contradistinction to those hitherto known, will normally have one of the longer sides of the stencil sheet secured throughout its length to the corresponding side of the backing sheet. 95

Adjacent to the line of connection between the backing sheet and the stencil sheet the material of the former may be thinned or frayed with a view to reducing 100 the possibility of rupture of the connection or injury to the stencil when in use.

To facilitate mounting the stencil sheet on the duplicating machine any convenient means may be employed. For instance, a 105 plurality of keyhole or other suitably formed

slots may be formed adjacent to the edge of the backing sheet opposite to that to which the stencil sheet is secured.

Alternatively, the material of the backing sheet may be locally weakened adjacent to the edge thereof remote from that to which the stencil sheet is connected to facilitate perforation of the edge by fastening means forming part of the duplicating machine.

19 A variety of other means of securing attachment between the stencil sheet and the fastening means on the duplicating machine may be employed.

20 In using a stencil in accordance with the invention the fastening means adjacent to one edge of the backing sheet will be connected with the fastening means on the duplicating machine and the remaining portion of the backing sheet, as well as the stencil, will be brought into contact with the stencil carrier.

21 In the normal operation of the machine ink will be transferred from the inking means on to the face of the backing sheet adjacent thereto and also on to the rear face of the stencil sheet. The ink will, however, only pass through the openings in the stencil sheet on to the stencil-receiving surface.

22 By the invention a number of advantages are secured. The first advantage arises from the fact that the means of making connection between the backing sheet and the stencil sheet is simplified, gumming or pasting devices of known character being suitable for the purpose in question.

23 The actual size of the stencil sheet is reduced, for instance a stencil sheet for use in producing an impression on a so-called foolscap sheet may have an area of substantially 13" x 8" or 13" x 9", whereas, as above indicated, in the known stencil sheets the actual stencil sheet for use in a similar manner measures approximately 16½" x 9" including the portion which is secured to the heading.

24 In addition, in such case, the size of the backing sheet is reduced and the necessity for modifying the diameter of the inking cylinders of a machine of the kind in which the flexible stencil carrier travels over a plurality of such rollers is obviated, and, as above explained, the reduction of the size of these rollers beyond certain limits is open to objection.

25 Further, where the machine is of the type adapted to print with inks of a plurality of colours or inks of different character and in which the lines of matter cut in the stencil are parallel with the direction of travel of the stencil, a stencil sheet in accordance with the invention for use in forming the body of the latter may be still further reduced in length.

26 If desirable or necessary, to the edge of the backing sheet an additional sheet of

paper may be secured so that when the combined stencil sheet is mounted on the machine the machine may be operated for a short period to cause the ink to pass through the stencil carrier and through the stencil itself on to this sheet which may then be detached and the stencil used in the normal manner.

27 In some cases the backing sheet may be provided with a detachable extension adjacent to the line of engagement of the backing sheet with the fastening means therefore, such portion being intended to be detached when the stencil sheet is mounted on the duplicating machine.

28 Certain constructions in accordance with the invention are illustrated by way of example in the accompanying drawings, in which:—

29 Figures 1, 2 and 3 show combined stencil sheets adapted for use with a duplicating machine in which the lines of the matter formed in the stencils will be arranged at right angles with the axis of the inking means of a duplicating machine.

30 In all of the constructions illustrated, 1 is the stencil sheet, 2 represents the main portion of the backing sheet of which the section 3 furnished with a plurality of keyhole slots 4 constitutes the means whereby the combined stencil sheet may be attached to the stencil carrier of the duplicating machine.

31 In the construction shown in Figure 1, the edge of the backing sheet which is of relatively thick paper is thinned or frayed with a view to reducing the possibility of rupture of the connection between the stencil sheet and the backing sheet or injury to the stencil when in use.

32 In all of the constructions, connection between the stencil sheet and the backing sheet is secured by pasting or gumming, thereby forming an overlap joint 6.

33 In Figure 3 a sheet 7 is shown detachably connected with and forming an extension of the backing sheet, while in Figure 2 the backing sheet is provided with an extension 8, which may be severed from the remaining portion thereof along the dotted line 9 where the material is perforated or otherwise weakened to facilitate such disconnection.

34 The extensions 7 or 8 may, if of hard or tough or ink-impermeable paper, perform one of the functions of the backing sheet in known constructions of stencil sheet; that is, when the stencil sheet is mounted on a rotary duplicator the extension may be left in position and the duplicator operated until the ink has been forced through the openings in the stencil and on to the extension when of course the latter will be detached.

35 Alternatively the extension may act as a "protector" sheet, such as are commonly

provided with so-called wax stencils, in which case it will be formed of tissue paper and will be located on the face of the stencil sheet directed away from the platen and towards the faces of type in the operation of stencilizing in a typewriter, whereas the extension if of hard or ink-impermeable paper will in the operation of stencilizing be located on the opposite side of the stencil sheet.

As will be understood extensions of both of the characters above indicated may be provided when desirable or necessary.

Having now described my invention what I claim as new and desire to secure by Letters Patent is:—

1. A combined stencil sheet comprising a sheet of tough paper, means adjacent to one edge of said sheet whereby the same may be secured in association with the inking means of a duplicator and secured to the opposite edge of said sheet, throughout the whole of the length of one side, a sheet adapted to be stencilized.
2. A combined stencil sheet adapted for use in duplicating machines of the kind in which the lines of matter cut in the stencil run at right angles to the axis of the inking means or parallel with the direction of motion of the stencil when in use, comprising a sheet of tough paper adapted to function as a backing sheet for the stencil sheet during stencilizing, means adjacent to one edge of said sheet whereby the same may be secured in association with the inking means of a duplicator and secured, throughout the whole length of one of its sides to the opposite edge of said backing sheet, a sheet adapted to be stencilized.
3. A combined stencil sheet comprising a sheet of tough paper, means adjacent to one

edge of said sheet whereby the same may be secured in association with the inking means of a duplicator and, secured to the opposite edge of said backing sheet throughout the whole of the length of one of its sides, a sheet adapted to be stencilized and in addition a sheet of paper secured so that when the combined stencil sheet is mounted on the machine the machine may be operated for a short period to cause the ink to pass through the stencil carrier and through the stencil itself on to this sheet which may then be detached and the stencil used in the normal manner.

4. A combined stencil sheet adapted for use in duplicating machines of the kind in which the lines of matter cut in the stencil run at right angles to the axis of the inking means or parallel with the direction of motion of the stencil when in use, comprising a sheet of tough paper adapted to function as a backing sheet for the stencil sheet proper during stencilizing, means adjacent to one edge of said backing sheet whereby the same may be secured in association with the inking means of a duplicator and, secured throughout the whole length of one of its sides to the opposite edge of said backing sheet, a sheet adapted to be stencilized, and in addition a sheet of paper secured so that when the combined stencil sheet is mounted on the machine the machine may be operated for a short period to cause the ink to pass through the stencil carrier and through the stencil itself on to this sheet which may then be detached and the stencil used in the normal manner.

In testimony whereof I have signed my name to this specification.

SIGMUND GESTETNER.
